(57) **CLAIM**

The ornamental design for an electric milk frother, as shown and described.

DESCRIPTION

FIG. 1 is a front, right and top perspective view of a first embodiment of an electric milk frother, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front, right and top perspective view of a second embodiment of an electric milk frother;

FIG. 9 is a front view thereof;

FIG. 10 is a rear view thereof;

FIG. 11 is a left side view thereof;

FIG. 12 is a right side view thereof;

FIG. 13 is a top plan view thereof; and,

FIG. 14 is a bottom plan view thereof.

1 Claim, 14 Drawing Sheets
